UNITED STATES PATENT OFFICE.

GEORGE WORDINGHAM, OF MILWAUKEE, WISCONSIN.

SHIRT-ENVELOP.

1,024,813.

Specification of Letters Patent.

Patented Apr. 30, 1912.

Application filed January 4, 1911. Serial No. 600,822.

To all whom it may concern:

Be it known that I, GEORGE WORDINGHAM, citizen of the United States, residing at Milwaukee, in the county of Milwaukee and

5 State of Wisconsin, have invented certain new and useful Improvements in Shirt-Envelops, of which the following is a specification.

This invention relates to wrappers and 10 more particularly to that class of wrappers especially designed to house and protect shirts and similar articles of wearing apparel after the latter have been laundered.

The object of the invention is to provide 15 a wrapper, the construction of which is such as to prevent soiling of a shirt, either when kept in stock or in the course of delivery to the owner, while at the same time admitting of inspection of the contents of the wrapper 20 so that the nature and style of the article housed therein may readily be determined.

A further object is to provide a wrapper including a back section having a strip of 25 relatively thin translucent material permanently secured thereto and covering one side thereof so as to form a garment receiving pocket gradually decreasing in size from one end of the back section to the other.

Further objects and advantages will appear in the following description, it being understood that various changes in form, proportions and minor details of construction may be resorted to within the scope of 30 the appended claims.

35 For a full understanding of the invention and the merits thereof, reference is to be had to the following description and accompanying drawings, in which:

Figure 1 is a perspective view of a shirt 40 wrapper constructed in accordance with my invention; Fig. 2 is a rear elevation of the same; Fig. 3 is a longitudinal sectional view, showing the garment receiving pocket open and in position to receive a shirt; Fig. 45 4 is a transverse sectional view taken on the line 4—4 of Fig. 1 and looking in the direction of the arrow, the front section of the wrapper being shown in full lines in normal position, and in dotted lines in distended position to permit the insertion of a shirt; Fig. 5 is a transverse sectional view taken on the line 5—5 of Fig. 1 and looking in the direction of the arrow; Fig. 6 is a longitudinal sectional view, partly in perspective, 50 55 showing the manner of housing the shirt within the garment receiving pocket.

Corresponding and like parts are referred to in the following description and indicated in all views of the drawings by the same reference characters.

60 The wrapper comprises an elongated back section 5, preferably formed of cardboard or other relatively stiff material, said section being of sufficient length to form a support for a shirt of standard size, and having its 65 opposite longitudinal edges disposed parallel with each other and its ends arranged at right angles to said edges, as shown. Extending across the front face of the back section 5, is a strip of relatively thin and preferably translucent material 6, such as tissue paper, which latter forms a housing for a shirt or other article to be protected. The 70 opposite longitudinal edges of the front section 6, are permanently secured to the rear 75 face of the back section 5, by folding the material comprising said front section inwardly over the adjacent longitudinal edges of said back section to form wedge-shaped 80 attaching flanges 7, which flanges are glued or otherwise fastened to the back section. The intermediate portion of the front section 6 is spaced slightly from the front face 85 of the back section 5 to form an intermediate pocket 8 adapted to receive a shirt, the opposite ends of the material forming the front section 6 preferably terminating short 90 of the adjacent ends of the back section 5 so as to facilitate inserting the shirt within the pocket, and also to form extended portions 95 or lips 9 at the opposite ends of the pocket which prevent damage to the shirt when throwing the wrappers containing the shirts into a delivery wagon or otherwise handling said wrappers.

95 It will here be noted that the front section 6 gradually increases in width from one end of the back section to the other end thereof, the excess material being extended laterally beyond the adjacent longitudinal edges of 100 the back sections, as indicated at 10, thus to produce a pocket gradually decreasing in depth, so as to conform to the shape of a shirt and thus permit the shirt to be readily inserted in the pocket without danger of 105 tearing the front section 6, or without causing the formation of wrinkles or folds in the garment.

110 The material forming the upper end of the front section 6 is preferably folded inwardly to form a reinforced edge 11 to assist in preventing tearing of the front section

when inserting a shirt within the pocket or removing said shirt therefrom.

Attention is here called to the fact that the front section 6 is drawn relatively tight 5 across the lower portion of the back section 5, while said front section is loose at the upper end of the back section so that when a shirt or other garment is inserted within the pocket 8, the material at the contracted end 10 of the pocket, will frictionally engage the shirt and thus effectually prevent accidental displacement thereof. It will also be noted that the back section 5 is substantially concavo-convex in cross section so that the 15 material comprising the front section 6 will be retained in position thereon without wrinkling, this concavo-convex formation of the back section also facilitating the insertion of the shirt within the pocket when the 20 opposite longitudinal edges of the back section are grasped in the hand and slightly flexed as shown in Fig. 6 of the drawings.

In using the wrapper, the small or thin end of a laundered shirt is inserted in the 25 mouth of the pocket 8, and a slight longitudinal pressure exerted on both the shirt and lower end of the back section, which causes the shirt to extend approximately half way within the pocket, after which the 30 wrapper is placed on end and the longitudinal edges of the back section slightly flexed which allows the shirt to drop by gravity until it is entirely housed within the pocket, the front section 6 at the contracted end 35 thereof, by frictional engagement with the thin end of the shirt, serving to retain the shirt within the pocket and effectually prevent accidental displacement thereof during transportation or shipment. The front sections 6 being permanently attached to the back section, the pocket is always in position 40 to receive a shirt, thus dispensing with the employment of locking tongues, flaps and similar auxiliary fastening device which are necessary and now in general use for securing 45 the outer section to the inner section.

It will of course be understood that the wrappers may be made in different standard sizes, and if desired, the front section 6,

instead of being translucent, may be made 50 of opaque material without departing from the spirit of the invention.

Having thus described the invention, what is claimed as new is:

1. A wrapper comprising a relatively stiff 55 back section and a relatively flexible front section, the front section being secured at its rear edge portions to the corresponding edge portions of the back section, the portion of the front section between its outer edge portions being of greater width at one end than the said back section, whereby to afford a pocket between the sections tapering from end to end.

2. A wrapper comprising a relatively stiff 65 back section and a relatively flexible front section, the front section being secured at its lateral edge portions to the corresponding edge portions of the back section, the portion of the front section between its attached edge portions being of greater width at one end than the back section at the corresponding end and at its other end being of substantially the same width as the back section at the corresponding end, whereby to 70 afford a pocket between the sections tapering from end to end.

3. A wrapper comprising a relatively stiff back section and a relatively flexible front section, the front section being secured at its 80 lateral edge portions to the corresponding edge portions of the back section, the portion of the front section between its attached edge portions being of greater width at one end than the back section at the corresponding end and at its other end being of substantially the same width as the back section at the corresponding end, whereby to 85 afford a pocket between the sections tapering from end to end, the said front section at 90 its end edge portions being unattached to the back section.

In testimony whereof, I affix my signature in presence of two witnesses.

GEORGE WORDINGHAM. [L. S.]
